UNITED STATES PATENT OFFICE

ARTHUR W. LYDA, OF NORTH CANTON, OHIO, ASSIGNOR TO INTERNATIONAL DAVIT & MANUFACTURING CORPORATION, A CORPORATION OF DELAWARE

DAVIT AND OPERATING MEANS THEREFOR

Application filed May 3, 1929. Serial No. 360,111.

The invention relates to davits such as are used upon steamships and the like for carrying lifeboats, and to mechanism for controlling the lowering and raising of the lifeboats.

5 The object of the improvement is to provide a davit constructed to provide for instant release of the life boat; to provide a pivoted or hinged upper portion upon the davit so arranged that when the cable supporting the 10 lifeboat is slackened, the weight of the boat will pull the pivoted portion of the davit outward to compensate for any list in the vessel upon which the same is mounted and allow the davit to go over the side of the ship; to 15 provide a latch upon the lower portion of the davit adapted to engage the keel of the lifeboat when in raised position, this latch being automatically opened by the tilting of the pivoted upper portion of the davit; to provide 20 means for moving the entire davit outward toward the edge of the ship when the lifeboat starts to lower, thus permitting the full davit to go over the side of the ship with the lifeboat suspended entirely away from 25 the side of the ship; to provide means for controlling the lowering of the lifeboat; to provide means for raising the lifeboat and davit and for moving the davit inward upon the deck when the same reaches the raised position; to provide a drum having cables running 30 to the davits of each lifeboat, said drum containing means for controlling the lowering and raising of the boat; to provide means for driving a plurality of these drums in unison from one motor or the like in order that several life-boats may be raised at the same time; to provide a governor controlled brake mechanism for regulating and controlling the speed at which the lifeboat may be lowered; and to 35 generally improve and simplify constructions of this kind.

The above and other objects may be attained by constructing the improved davit and control mechanism in the manner illustrated in the accompanying drawings, in which

Figure 1 is a side elevation of a lifeboat suspended from the improved davits and showing the control mechanism associated therewith;

Fig. 2, an end elevation of the same;

Fig. 3, a top plan view of the improved control mechanism with the cover plate removed and parts broken away for the purpose of illustration; and

Fig. 4, a vertical sectional view through the same.

Similar numerals refer to similar parts throughout the drawings.

The deck of a ship is indicated at 10 and the bases upon which the davits are slidably mounted are shown at 11, being spaced apart in pairs, as indicated in Fig. 1, a suitable distance to accommodate the lifeboat shown generally at 12.

Each of the base plates is provided near each end with an upright flange 13, reinforcing webs 14 or the like being preferably provided for strengthening the same. A carriage 15 is mounted upon each base 11, as by means of the rollers 16, and adapted to move endwise upon the base, being slidably mounted upon the rod 17 which is connected to the flanges 13.

The plate 18 is hingedly connected to the forward end of the carriage as at 19, the davit proper being mounted upon said plate and comprising the normally vertical uprights 20 and the outwardly inclined uprights 21 connected together at their upper ends as at 22. A pivoted or hinged upper section 23 is pivotally connected to the juncture of the uprights 20 and 21 as at 24 and is provided at its upper end with a pulley 25 and upon its rear side, at a point intermediate its ends, with a smaller pulley 26.

A bracket 27 is fixed upon the forward side of the davit, below the pivotal point 24, for engagement with the end portion 28 of the keel of the lifeboat which is adapted to be normally held tightly against the bracket by means of a clamping plate 29 pivoted on a vertical axis, as indicated at 30, upon the arm 31 pivoted at its upper end as at 32 upon a bracket 33 fixed upon the uprights 20.

This clamping plate is provided with an arm 34 adapted to contact with the U-shaped bracket 35 to move the plate into clamping position against the keel when the davit is in raised position, as shown in Figs. 1 and 2.

5 The pivoted upper portion 23 of the davit is provided with a depending arm 36, the lower end of which is pivotally connected, as at 37, to one end of a link 38, the other end of which is pivoted as at 39 to the upper end of the lever 31.

10 For the purpose of limiting the outward swinging movement of the davit, as shown in the broken line position in Fig. 2, cables 10 40 are connected to the base plate 11, as shown at 41, and extend below the rollers 16 and are then extended upward and connected to lugs 42 upon the uprights 20.

15 The lifeboat is suspended upon the cables 15 43 provided at their ends with hooks or shackles 44 which may be of the quick releasing type as disclosed in my prior Patent No. 1,675,896, dated July 3, 1928.

20 These cables extend upward from the lifeboat around the pulleys 25, then downward over the pulleys 26 and around the pulleys 45 and 46 mounted upon the bracket 47 carried by the hinged plate 18, the cables then extending toward each other, as indicated in 25 Fig. 1, and being connected to the drum upon the controlling mechanism which will be hereinafter described.

25 The improved controlling mechanism for raising and lowering the lifeboat, as shown 30 in Fig. 1, comprises a unit mounted upon the deck between the davits for each boat, the same being indicated generally at 48 in said figure.

35 A plate 49 is fixed upon the deck and provided with the upright rim flange 50 within which is journaled the drum 51 having the internal gear 52 meshing with a gear 53 journaled upon a shaft 54 carried by the boss 55 upon the upper side of the plate 49.

40 The gear 53 meshes with a pinion 56 mounted upon the central shaft 57 journaled at its lower end in the boss 58, formed upon the base plate, the upper end of the shaft being journaled in the cover plate 59 which is fixed to the upper end of the drum as by the screws 60.

45 A peripheral flange 61 is formed around the lower portion of the drum and provided with the ratchet teeth 62 arranged to be engaged by a pawl 63 pivoted, as at 64, upon the ring 65.

50 This ring is fixed to the deck surrounding and concentric with the base plate 49 and provided with the upright flange 66 and the 55 annular inwardly disposed flange 67 which overhangs the peripheral flange 61 upon the drum.

55 A spring 68 or the like may be provided beneath the tail 69 of the pawl for normally holding the same in engagement with the ratchet teeth 62.

60 A pair of reels 70 is fixed upon the periphery of the drum 51, one of the cables 43 being wound around each reel. A sprocket wheel 65 71 is fixed upon the peripheral portion of the

drum, preferably near the upper end thereof and is engaged by the sprocket chain 72 which may be connected to the sprockets of a plurality of the drums and driven by a motor or the like, whereby several lifeboats may be operated simultaneously by means of the same motor.

65 A pair of diametrically opposed arms 73 is fixed upon the vertical shaft 57 and a sleeve 74 is slidably mounted upon each arm, each sleeve carrying a shoe 75 adapted to frictionally engage the inner surface of the drum.

70 For the purpose of controlling the speed of the drum, in the direction to permit the lifeboat to be lowered, a governor is provided for automatically bringing the shoes into frictional contact with the drum when the boat is descending at too great a speed.

75 This governor comprises a fan blade 76 carried upon an angular lever 77 pivoted as at 78 to a bracket 78 carried by each of the arms 73, the inner end of the lever contacting with the inner end of the adjacent sleeve 74, whereby rotation of the drum in the direction of the arrow shown in Fig. 3 will tend to throw the fan in the opposite direction, forcing the shoe outward against the inner surface of the drum.

80 For the purpose of manually braking the speed of the drum, a lever 79 may be fulcrumed at one end as at 80 upon an upright 81 carried by the ring plate 65, this lever extending diametrically across the drum and spaced therefrom. A depending boss 82 is 85 carried by the lever and adapted to contact with the disk 83 having posts 84 slidably located through suitable openings in the top plate 59 and carrying a disk 85 at their lower ends.

85 This last named disk is arranged to contact with a similar disk 87 slidably mounted upon the shaft 57 and provided with depending pins 88 passed through elongated openings 89 in the links 90, these links being connected at their other ends to lugs 91 upon the sleeves 74. A cord or cable 92 is attached to the free end of the lever 79 and may have its end located in the lifeboat, as shown in Fig. 1.

90 In the event it is desired to stop the descent of the boat at any point, a person within the lifeboat may pull downward upon the cord 92, swinging the lever 79 downward upon its fulcrum and tending to move the inclined links 90 toward a horizontal position, forcing the shoes 75 into frictional contact with the inner walls of the drum and braking the movement thereof.

95 In the operation of the apparatus, assuming the lifeboat to be in raised position, as shown in Figs. 1 and 2, when it is desired to lower the boat, the pawl 63 is moved out of engagement with the ratchet teeth 62, thus permitting the weight of the lifeboat, through 100

the cables 43, to rotate the drum and permit the cables to unwind therefrom.

The cables being thus slackened, the weight of the lifeboat will cause the pivoted upper sections 23 of the davits to swing outward and the clamp plates 29 will swing upon the pivots, releasing the lifeboat, permitting it to swing outward.

As the davits swing outward, due to the weight of the lifeboat, the carriages upon which the davits are mounted will slide toward the outer edge of the deck and the tension upon the cables 40 being released, the davits will assume substantially the broken line position shown in Fig. 2, the cables 40 assuming the position shown in broken lines in said figure and holding the davits in this position.

The lifeboat will thus be swung out, well away from the side of the ship and will continue to descend until it strikes the surface of the water. In the event the descent is too rapid, the governor mechanism above described will force the shoes 75 into frictional contact with the inner surfaces of the drum, slowing up the speed thereof.

If it is desired to stop the lifeboat at any time during the descent, a person in the boat may pull downward upon the cord 92, thus through the links 90 bringing the shoes 75 into braking contact with the inner surfaces of the drum.

When it is desired to raise the lifeboat, the motor is operated, turning the drum through the chain 72 and sprocket 71, in a direction to rewind the cables 43 upon the wheels 70. The davits will thus be pulled back to the initial position, as shown in Figs. 1 and 2, and the lifeboat clamped between the clamp plates 29 and held in this position.

In order to provide for disconnecting the drum from the driving means, the sprocket 71 may be rotatably mounted upon the drum, and provided as upon its upper face, with the ratchet teeth 95, arranged to be engaged by the pawl 96, which is pivotally mounted upon the cam plate 59 of the drum.

I claim:

1. Davits for a ship's lifeboat including an upright, a pivoted upper section upon the upright, a clamp upon the upright for holding the lifeboat against the upright, a pulley upon the pivoted section, a cable attached to the lifeboat and located over said pulley, and means for permitting the pivoted section to swing outward and for opening the clamp when the cable is slackened.

2. Davits for a ship's lifeboat including an upright, a pivoted upper section upon the upright, a clamp upon the upright for holding the lifeboat against the upright, a pulley upon the pivoted section, a cable attached to the life boat and located over said pulley, and means for permitting the pivoted section to swing outward and for opening the clamp

when the cable is slackened, the clamp being operatively connected to the pivoted section.

3. Control apparatus for davits and the like including a rotatable drum, a cable having one end wound upon the drum, an internal gear in the drum, a shaft journaled within the drum and operatively connected to said gear, an arm upon the shaft, a shoe slidably upon said arm, and a fan blade pivoted upon the arm and arranged to force the shoe into frictional contact with the inner surface of the drum when the drum is rotated.

4. Control apparatus for davits and the like including a rotatable drum, a cable having one end wound upon the drum, an internal gear in the drum, a shaft journaled within the drum and operatively connected to said gear, an arm upon the shaft, a shoe slidably upon said arm, a fan blade pivoted upon the arm and arranged to force the shoe into frictional contact with the inner surface of the drum when the drum is rotated, a ratchet upon the drum, and a pawl for normally engaging the ratchet.

5. Control apparatus for davits and the like including a rotatable drum, a cable having one end wound upon the drum, an internal gear in the drum, a shaft journaled within the drum and operatively connected to said gear, an arm upon the shaft, a shoe slidably upon said arm, a disk slidable upon the shaft, a link connecting the disk and shoe, and a lever for moving the disk upon the shaft to force the shoe into frictional contact with the inner surface of the drum.

6. Control apparatus for davits and the like including a rotatable drum, a cable having one end wound upon the drum, an internal gear in the drum, a shaft journaled within the drum and operatively connected to said gear, an arm upon the shaft, a shoe slidably upon said arm, a fan blade pivoted upon the arm and arranged to force the shoe into frictional contact with the inner surface of the drum when the drum is rotated, a sprocket upon the drum, and a driven chain connected to the sprocket.

7. Control apparatus for davits and the like including a rotatable drum, a cable having one end wound upon the drum, an internal gear in the drum, a shaft journaled within the drum and operatively connected to said gear, an arm upon the shaft, a shoe slidably upon said arm, a fan blade pivoted upon the arm and arranged to force the shoe into frictional contact with the inner surface of the drum when the drum is rotated, a ratchet upon the drum, a pawl for normally engaging the ratchet, a sprocket upon the drum, and a driven chain connected to the sprocket.

8. Control apparatus for davits and the like including a rotatable drum, a cable having one end wound upon the drum, an internal gear in the drum, a shaft journaled

within the drum and operatively connected to said gear, an arm upon the shaft, a shoe slideable upon said arm, a disk slideable upon the shaft, a link connecting the disk and shoe, a lever for moving the disk upon the shaft to force the shoe into frictional contact with the inner surface of the drum, a sprocket upon the drum, and a driven chain connected to the sprocket.

5 9. Davits for a ship's lifeboat including a carriage adapted to move toward the edge of the deck, an upright hingedly mounted upon the carriage and adapted to swing outwardly, operative means connected between the upright and the carriage for automatically moving the carriage toward the edge of the deck when the upright is swung outward.

10 10. Davits for a ship's lifeboat including a carriage adapted to move toward the edge 20 of the deck, an upright hingedly mounted upon the carriage, a pulley at the upper portion of the upright, a cable located over said pulley for supporting a lifeboat, means permitting the upright to swing outward due to 25 the weight of the boat when the cable is slackened, and means operatively connected to said upright for moving the carriage toward the edge of the deck when the upright is swung outward.

20 11. In testimony that I claim the above, I have hereunto subscribed my name.

ARTHUR W. LYDA.
